UNITED STATES PATENT OFFICE.

ALBERT G. ELVIN, OF FRANKLIN, PENNSYLVANIA.

AXLE-BOX LUBRICATOR.

No. 818,021.

Specification of Letters Patent.

Patented April 17, 1906.

Application filed July 8, 1905. Serial No. 268,585.

To all whom it may concern:

Be it known that I, ALBERT G. ELVIN, of Franklin, in the county of Venango and State of Pennsylvania, have invented a certain new and useful Improvement in Axle-Box Lubricators, of which improvement the following is a specification.

My invention relates to axle - box lubricators of the class or type in which oil is applied to the journal by wicks extending into an oil cellar or reservoir located below the same; and its object is to provide means of simple and inexpensive construction and ready applicability in axle-boxes of the ordinary construction whereby the supply of oil to the journal may be properly and fully effected and the necessity of furnishing a fresh supply of oil to the cellar shall be indicated in accordance with its consumption without requiring the removal of any portion of the apparatus for the purpose of ascertaining it.

The improvement claimed is hereinafter fully set forth.

In the accompanying drawings, Figure 1 is a front view in elevation of a locomotive driving-axle box in which my invention is applied; Fig. 2, a vertical transverse section through the same; Fig. 3, a vertical longitudinal section with the wicks removed to show the construction more clearly; and Figs. 4 and 5, partial transverse sections, on an enlarged scale, through the oil-cellar, showing modifications of structural detail.

My invention is herein exemplified as applied in a driving-axle box 2, which is adapted to be supported on one of the journals of a locomotive-engine axle and which is fitted with the usual brass bearing 3 and lower oil-cellars 4, the latter being held removably in place by rods 7, passing through lugs 5 on the oil-cellars and adjoining lugs 6 on the box.

The top of the oil-cellar 4 is covered by a cap-plate 11, of sheet metal, which is curved transversely to approximately the radius of the journal on which the axle-box is carried. The plate 11 fits closely in the top of the cellar and is turned downwardly on its sides to form short vertical flanges which fit against the sides of the cellar. A plurality of longitudinal wick-slots 12 is formed in the cap-plate, said slots engaging the upper ends of wicks 13, which depend therefrom into the cellar and carry therefrom to the surface of the journal the oil with which the cellar 4 is from time to time supplied in accordance with the requirements of service of the axle. The

slots 13 are distributed as uniformly as may be throughout the surface of the cap-plate, and the latter is held in position relatively to the journal by one or more light springs 16, two 60 being shown in this instance.

It will be seen that by the provision of wick-slots and wicks, which are distributed over the surface of the cap-plate, so as to enable the wicks to make contact with the journal at numerous points in its periphery, the supply of oil thereto is effected more thoroughly and uniformly than if applied only on one or two longitudinal lines, as has ordinarily heretofore been the practice. 70

In the operation of axle-boxes in which oil is used for lubrication, particularly when, as in locomotives, they are located inside the frames, difficulty has been experienced by reason of the fact that it was not practicable 75 to ascertain when the oil-cellar required to be refilled, and failure to maintain a sufficient supply of oil, which was often due to this, resulted in more or less damage to machinery and delays to trains. In order to overcome 80 this objection, I provide the oil-cellar with a float, which is supported on the oil therein and carries an indicator projecting to the outside of the cellar, by which the exhaustion of oil therefrom to such a degree as to require 85 a further supply may be observed without necessitating the detachment of the cellar or any part thereof for the purpose of ascertaining what amount of oil may remain therein. 90

As shown in Figs. 2 and 3, a float 18, which may be either a hollow cylinder of light sheet metal or be made of cork or other buoyant material, is fitted to rest upon the surface of the oil in the cellar 4 and to traverse vertically in a guide 15, which is in the form of a 95 cylinder cast integral with the bottom plate of the cellar and having a lateral opening through which the oil enters, so as to stand at the same level in the guide as in the surrounding interior space of the cellar. An 100 indicator-rod 14, fixed to the float, is bent into U form and fits freely in a vertical passage formed in the wall of the guide 15 and extending through the same to the exterior of the cellar. The top of the guide and the 105 indicator-rod are covered by a cap 18^b, which prevents the wicks 13 from interfering with the movements of the float. As the level of the oil in the cellar falls, by reason of its consumption, the float 18 correspondingly descends, causing the indicator-rod 14 to protrude below the cellar when the oil reaches so 110

low a level therein as to require the resupplying thereof. The engineer or roundhouse operative can by observing or feeling the indicator-rod be made aware that the cellar 5 should be resupplied with oil.

Figs. 4 and 5 illustrate floats which consist in each case of a cup of light sheet metal having an indicator-rod 14 fixed to its center and projecting downwardly therefrom within a guide formed of a tube 17, which is connected to the bottom of the cellar, the bore of the tube 17 extending to the exterior thereof, so that the indicator-rod may protrude therefrom when the level of 15 the oil is sufficiently lowered, as in the instance first described. As shown in Fig. 4, the metal of the float is turned upwardly at its bottom, so as to form a supplemental cap 18, the air within which adds to the buoyancy of the float. In each of the last above-described instances a vertical guard 4^a is cast upon the bottom of the cellar to prevent the movement of the float being interfered with by the wicks, and in Fig. 4 a cap 18^b is 25 shown as added to the guard.

I claim as my invention and desire to secure by Letters Patent —

1. In an axle-lubricator, the combination of an oil-cellar, a float fitted to traverse vertically in the cellar, and an indicator-rod 30 connected to said float and adapted to project below the bottom of the cellar when the float stands at or below a determined level therein.
2. In an axle-lubricator, the combination of an oil-cellar, a float fitted to traverse vertically in the cellar, an indicator-rod connected to said float, and a vertical passage ex- 35

tending through the bottom of the cellar, through which said indicator-rod passes and 40 from which it projects when the float stands at or below a determined level in the cellar.

3. In an axle-lubricator, the combination of an oil-cellar, an inwardly-curved cap-plate located at the top of said cellar and perforated by wick-slots, wicks engaging said slots and extending therefrom to the lower portion of the cellar, a float fitted to traverse vertically in the cellar, an indicator-rod 45 connected to said float and adapted to project below the bottom of the cellar when the float stands at or below a determined level therein, and means for preventing the wicks from interference with the movements of the float.

4. In an axle-box lubricator, the combination of an oil-cellar, an inwardly-curved cap-plate located at the top of said cellar and 50 perforated by wick-slots, wicks engaging said slots and extending therefrom to the lower portion of the cellar, a float fitted to traverse vertically in the cellar, an indicator-rod 55 connected to said float and adapted to project below the bottom of the cellar when the float stands at or below a determined level therein, and a guard interposed between the float and the adjacent wicks.

5. In an axle-box lubricator, the combination of an oil-cellar, a vertical tube fixed to and extending through the bottom of the cellar, an indicator-rod fitting freely in said 70 tube, and a cup-shaped float fixed to the upper end of the indicator-rod.

ALBERT G. ELVIN.
